CLAIM

The ornamental design for a bracket, as shown and described.

DESCRIPTION

FIG. 1 is a perspective view of a bracket, showing my new design;

FIG. 2 is a back perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof;

FIG. 8 is a bottom plan view of thereof; and,

FIG. 9 is an exploded perspective view showing the bracket of FIGS. 1 through 8 being used, by way of example only, with an exemplary wall standard and L-shaped member.

The details shown in broken lines are for illustrative purposes only and form no part of the claimed design.
